UNITED STATES PATENT OFFICE

123,939

DESIGN FOR A PRICE TAG MARKING MACHINE

Thomas G. Turner, Dayton, Ohio, assignor to
Monarch Marking System Company, Dayton,
Ohio, a corporation of Ohio

Application April 26, 1940, Serial No. 91,962

Term of patent 14 years

To all whom it may concern:

Be it known that I, Thomas G. Turner, a citizen of the United States, residing at Dayton, in the county of Montgomery and State of Ohio, have invented a new, original, and ornamental Design for a Price Tag Marking Machine, of which the following is a specification, reference being had to the accompanying drawings, forming a part thereof,

Figure 1 is a perspective view of a price tag marking machine showing my new design.

Figure 2 is a rear elevational view thereof.

Figure 3 is an end elevational view.

I claim:

The ornamental design for a price tag marking machine, as shown.

THOMAS G. TURNER,
